US00D969811S

(12) **United States Design Patent** (10) **Patent No.:** **US D969,811 S**
(45) **Date of Patent:** **** Nov. 15, 2022**

(54) **ELECTRONIC DEVICE**

(71) Applicant: **Snap Inc.**, Santa Monica, CA (US)

(72) Inventors: **Dylan Shane Eirinberg**, Venice, CA (US); **Kyle Goodrich**, Venice, CA (US); **Andrew James McPhee**, Culver City, CA (US); **Daniel Moreno**, Los Angeles, CA (US)

(73) Assignee: **Snap Inc.**, Santa Monica, CA (US)

(**) Term: **15 Years**

(21) Appl. No.: **29/788,108**

(22) Filed: **Mar. 16, 2021**

(51) LOC (13) Cl. **14-02**

(52) U.S. Cl.

USPC **D14/374**; D6/300

(57) **CLAIM**

The ornamental design for an electronic device, as shown and described.

DESCRIPTION

FIG. 1 is a front view of an electronic device, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top-front-left perspective view thereof;

FIG. 8 is a bottom-front-right perspective view thereof;

FIG. 9 is a top-rear-left perspective view thereof; and,

FIG. 10 is a bottom-rear-right perspective view thereof.

The shade lines show surface contour.

1 Claim, 7 Drawing Sheets
